(57) **CLAIM**

The ornamental design of a utensil handle for knife, fork, teaspoon and soup spoon, as shown and described.

DESCRIPTION

FIG. 1 is a right side elevational view of the utensil handle with a knife blade, shown in dotted;

FIG. 2 is a left side elevational view of the utensil handle with a knife blade, shown in dotted;

FIG. 3 is a top plan view of the utensil handle with a knife blade, shown in dotted;

FIG. 4 is a bottom plan view of the utensil handle with a knife blade, shown in dotted;

FIG. 5 is a top plan view of the utensil handle shown with a fork end, shown in dotted;

FIG. 6 is a bottom plan view of the utensil handle shown with a fork end, shown in dotted;

FIG. 7 is a right side elevational view of the utensil handle with a fork end, shown in dotted, with the left side elevational view being a mirror image of the right side elevational view;

FIG. 8 is a top plan view of the utensil handle with a spoon end, shown in dotted;

FIG. 9 is a bottom plan view of the utensil handle with a spoon end, shown in dotted;

FIG. 10 is a right side elevational view of the utensil handle with a spoon end, shown in dotted, with the left side elevational view being a mirror image of the right side elevational view;

FIG. 11 is a top plan view of the utensil handle with a soup spoon end;

FIG. 12 is a bottom plan view of the utensil handle with a spoon end; and,

FIG. 13 is a right side elevational view of the utensil handle with a soup spoon end with the left side elevational view being a mirror image of the right side elevational view.

The broken lines shown are included for the purpose of illustrating different of eating utensils ends that form no part of the claimed handle design.
